(57) **CLAIM**

The ornamental design for a 3D hand held lidar as shown and described.

DESCRIPTION

FIG. 1 is a perspective view of the design.

FIG. 2 is a front view of the design.

FIG. 3 is a rear view of the design.

FIG. 4 is a left side view of the design.

FIG. 5 is a right side view of the design.

FIG. 6 is a top view of the design; and,

FIG. 7 is a bottom view of the design.

Portions shown in fine and discontinuous lines in FIG. 1 are for representing the curves.
